Application September 15, 1933, Serial No. 689,512

30 Claims. (Cl. 270—5)

The present invention relates to printing presses and more particularly to a novel and improved rotary printing press adapted for the printing of newspapers at high speeds.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

20 Figure 1 is a diagrammatic side elevation of a printing press embodying the present invention, and looking towards the left side of such a press;

Figure 2 is a side elevation of a single printing unit constructed in accordance with the present invention, and looking at the left side of the unit;

Figure 3 is a side elevation, corresponding to Figure 2, but showing the right side of the unit;

Figure 4 is a fragmentary detailed vertical section taken on the line 4—4 of Figure 10 and showing the gears for driving the printing couples, certain parts being omitted;

Figure 5 is a section taken on the line 5—5 of Figure 4;

Figure 6 is a fragmentary vertical section taken on the line 6—6 of Figure 9;

Figure 7 is a fragmentary section taken on the line 7—7 of Figure 4;

Figure 8 is a fragmentary plan view of the printing unit shown in Figures 2 and 3, and showing the right side of the unit;

Figure 9 is a similar view of the left side of the unit;

Figure 10 is a fragmentary vertical section taken on the line 10—10 of Figure 2;

Figure 11 is a horizontal section taken on the line 11—11 of Figure 10;

Figure 12 is a fragmentary vertical section showing the vertical drive shaft, and taken on the line 12—12 of Figure 2;

Figure 13 is a fragmentary vertical section of the gearing for driving the vertical shaft from the main shaft and taken on the line 13—13 of Figure 12;

Figure 14 is a sectional view of the ink fountains for a single unit and taken on the line 14—14 of Figure 15;

Figure 15 is a plan view of the ink fountains for a single printing unit as shown in Figures 2 and 3, with the printing couple, inking drums and side frames removed;

Figure 16 is a section taken on the line 16—16 of Figure 15;

Figure 17 is a fragmentary horizontal sectional view of the right end of the ink fountain and showing the ductor roll operating mechanism;

Figure 18 is a fragmentary end view of the ink fountain and ductor roll operating mechanism, with the casing and certain other parts shown 15 in section;

Figure 19 is a vertical sectional view taken on the line 19—19 of Figure 21;

Figure 20 is a similar sectional view of the other end of the inking drums and ink fountain;

Figure 21 is a fragmentary end view of the right side of the inking mechanism and drive therefor, with certain parts shown in section as taken on the line 21—21 of Figure 19, and other parts being broken away;

Figure 22 is an exploded view, with certain parts shown in section, of a printing unit in accordance with the present invention, and illustrating the method of disassembling the unit for shipment.

The present invention has for its object the provision of a novel and improved printing press particularly adapted for use in the printing of newspapers at high speeds. A further object is the provision of a newspaper printing press having an improved lubrication system which insures constant and thorough lubrication of all bearing surfaces and driving gears. Still another object is the provision of a printing press which can be shipped in a partially assembled state, and can be completely assembled by relatively unskilled workmen.

The invention further provides a novel and improved driving means for the individual printing units, improved bearing adjustment for varying the pressure between the plate and impression cylinders. The invention also provides novel and improved means for reversing one of the printing couples of a unit so that the web to be printed may be perfected or printed in multi-color.

In accordance with the present invention, the printing press comprises a plurality of printing units and one or more folding units preferably arranged in line, each printing unit comprising a pair of printing couples adapted to perfect a

web, and which may, if desired, be reversed to print the web in multi-color. As embodied, suitable driving means are provided for each of said units, and a drive shaft connecting said units 5 extends alongside said line of units. Between each printing unit is provided a clutch in the drive shaft whereby the line of units may be divided at any one or more desired points, and means are provided for driving the individual 10 units by means of individual drive shafts driven from the main shaft through a coupling which can be silenced at will.

As embodied, each of the units comprises a pair of printing couples, each provided with inking 15 mechanism comprising ink drums arranged in substantially vertical alignment with the plate cylinder of the couple and driven from the plate cylinder, together with the usual inking rollers.

Means, driven by the vertical drive shaft, are 20 provided for driving the fountain roller and vibrating the inking drums, and other means, driven by the fountain roller, are provided for operating the ductor roll to transfer ink from the fountain roll to the inking rollers and drums and thence 25 to the plate cylinder.

In the embodied form of the invention, the gearing for driving the vertical drive shaft from the main drive shaft is formed as a removable unit to facilitate assembly at the printing plant.

30 The cylindrical body portions of the inking drums and fountain roller are preferably provided with detachable flanges and shafts at their ends whereby the drums and roller can be removed without removing their shafts and gears from the 35 side frames in which they are journaled. After removing these relatively heavy bodies, the cylinders and the gearing units, the side frames may be shipped with certain of the shafts, bearings and gears in place, thereby avoiding the extensive 40 disassembly and reassembly which has heretofore been necessary for shipping newspaper printing presses.

The inking rollers for transferring ink from one inking drum to another and to the plate 45 cylinder are preferably mounted in hangers which receive the anti-friction bearing at the ends of the rollers, and these hangers are preferably adapted to pivot about either or both of two spaced pivots so as to permit accurate positioning 50 of the inking rollers with respect to both inking drums or an inking drum and the plate cylinder. Improved means are also provided for varying the pressure between the plate and impression cylinders as may be required for printing.

55 As embodied, means are provided for continuously circulating a relatively large amount of lubricant and for supplying it to the various bearings and gears of the unit, and these means preferably comprise a pump driven by the press and 60 supplying oil under pressure to the various meshes of gears near the top of the unit and to the heavy bearings, as well as other means for receiving the excess oil from the gears and bearings and leading it to the other lighter bearings and 65 the meshes of gears operating under relatively light pressure.

The excess oil on the drive side of the press is finally collected and received in the gearing unit mounted on the main drive shaft to provide a relatively deep oil bath for these gears, and from 70 this point is then led to the oil pump.

75 It will be understood that the foregoing general description and the following detailed description as well are exemplary and explanatory of the invention but are not restrictive thereof.

Referring now in detail to the illustrative embodiment of the invention as shown in the accompanying drawings, the printing press comprises a plurality of printing units 1 which may be of identical construction and are arranged in line 5 with each other to supply the webs printed by them to a folding unit 2, also in line with the printing unit. Any suitable number of printing units 1 and folding units 2 may be employed, with the folding units preferably interposed between 10 the printing units.

The folding units 2 may be of conventional construction comprising the usual former 3 and transverse folding cylinders 4, adapted to associate, longitudinally fold, cut, transversely fold and 15 deliver as separate products the various webs printed by the printing units 1.

The printing units 1 each comprise a pair of printing couples adapted to perfect a web of paper, each couple comprising an impression cylinder 5, and a printing cylinder 6 which is provided with the usual parti-cylindrical printing plates. Impression cylinders 5 and printing cylinders 6 may be of substantially conventional construction, and for that reason are not described 20 in detail. One of cylinders 6, at the rear of the unit, is rotatably mounted in the side frames 8 by means of its projecting shaft ends 7 and roller bearings 9 which are seated in annular sleeves 10. Bearings 9 are held within their sleeves 10 by means of flanges 11 and 12 which are bolted to the opposite sides of sleeves 10, while sleeves 10 are held against angular or axial movement by means of screws 13 passing through the flange 14, integral with sleeve 10, and threaded into the 30 frame 8.

Cylinder 5, cooperating with the first or second impression cylinder 6 to form the rear couple of the unit, is likewise mounted in the frames 8 by means of its projecting shaft ends 15 on which are 35 mounted roller bearings 16 seated in eccentric annular sleeves 17, and retained therein by means of flange 18, at the right, or by a capping plate 19 at the left end.

The cylinders 5 and 6 of the forward printing 45 couple are mounted in a manner generally similar to those of the rear couple, except that in the illustrative embodiment one end of cylinder shaft 7 is covered by means of a plate 19 which also serves to hold the end bearing 9 in place, whereas 50 in the rear couple the cap 19 is applied to the left shaft end 15.

At one end of the cylinders, the bearings 9 and 60 16 are held apart by means of a spacer ring 20 positioned between the outer races of the bearings and are a sliding fit in their supporting sleeves, whereas at the other end of the cylinders the bearings are held apart by spacing ring 21 positioned between the inner races of the bearings and are a press fit on the cylinder shaft. At the ends, 65 the inner bearings abut against the ring 22 fitted to a shoulder of the shaft 7 or 15. The inner race of the outer bearings 9 or 16 is pressed inwardly by means of a spacer ring 23 fitted closely to the shaft and extending between the inner race and an abutting gear or capping plate.

Means are provided for varying the pressure exerted during printing between the plate cylinder 6 and impression cylinder 5, and for this purpose eccentric sleeves 17 may be minutely 70 angularly moved to and held in any desired position. As embodied, each sleeve 17 is provided with a pair of diametrically opposed radially extending ears 24 which project into a correspondingly enlarged portion 25 of the frame re- 75

cess in which sleeve 17 is seated. Sleeves 10 and 17 are held in place by means of the frame capping member 26 which is secured to the main portion of frame 8 by bolts 27. Opposed screw-threaded members are provided adapted to bear against the ears 24, and as embodied screws 28 are provided on opposite sides of the sleeve 17 and are threaded into the capping plate 26, extending upwardly so as to have their heads accessible from the upper part of the press frame. Screws 28 may be tightened against the ears 24 to hold the eccentric sleeve 17 in any desired position, or by loosening one screw 28 and tightening the other, the eccentric sleeve may be angularly moved to any desired position, in which it may be held by tightening the loosened screw.

Means are provided for rotating the cylinders 5 and 6 of both couples in register, and for this purpose a gear 30 is keyed on a shaft of the forward cylinder 5, and a gear 31 of similar size is keyed to the shaft 7 of the rear cylinder 6, gears 30 and 31 meshing with a driven gear 130 carrying the drive. At their right-hand ends, the impression cylinder 5 and plate cylinder 6 are provided with gears 33 and 34 mounted on shafts 15 and 7 respectively, these gears meshing together so that the impression cylinder 5 is driven from the plate cylinder 6.

For the forward couple, gear 30 drives the impression cylinder 5 and at its right hand end a gear 35 is mounted on shaft 15 and keyed thereto, meshing with a gear 36 keyed to the shaft 7 of plate cylinder 6. By this construction, the plate cylinders of one couple are driven in a direction opposite to that of the plate cylinders of the other couple, permitting the web to be perfected when it is threaded in the manner shown in Figure 1 of the drawings.

Gears 30 to 36 are keyed to their respective shafts and are held in position thereon by means of capping plates 37 and screws 38, certain of the screws being passed through apertures in the plate 37 and threaded into the shaft end, while others of these screws 38 are threaded into the hub portion of the gear.

Side frames 8 are preferably substantial duplicates of each other, and each comprises a member having a general shape of an inverted U, formed from a single slab of heavy metal having its two sides planed to make it of uniform thickness. The two side frames are preferably bored in superposed relation, all of the holes being bored without changing the relative position of the slabs, thereby insuring proper alignment of all the bearing mountings and other parts.

The bottom portion of the frame members 8 is preferably planed to provide a flat surface to rest against the bed frames 40 and to which the frame members 8 may be securely bolted. The frame members 8 are preferably spaced apart and held rigid with respect to each other by means of a slotted cross brace or tie-plate 41 extending between the inner sides of the frames. Tie-plate 41 is preferably positioned between and slightly below the impression cylinders 5, and comprises a plurality of irregularly shaped bars extending the width of the press and formed integrally with a flange 42 at each end, flange 42 being bolted to the frame 8 by screws 43. Between the cross bars 44 are narrow slots 45, extending from one side of the press to the other and through which the web may be run. At their lower ends, the frame members 8 are braced and held rigid by means of the ink fountain, as will later be described in detail.

Means are provided for driving the cylinders of the several units in synchronism with each other so that the several webs may be associated in register prior to folding, and these means also preferably permit the several units to be divided into various groupings, or to permit any one or more units to be silenced while the adjacent units are coupled together into a single unit.

As embodied, a main drive shaft 50 is divided into a plurality of axially aligned sections extending alongside of the several printing units 1 and folding units 2 which are coupled together by means of clutches 52, one clutch being provided between each pair of units. The several sections of shaft 50 are rotatably mounted by means of suitable bearings supported in brackets 53 attached to the side of the bed frame 40.

For driving each of the units, there is provided a gear unit positioned in line with the shaft 50 and at one side of the printing unit, and these gear units 55 are shown in detail in Figures 12 and 13 of the drawings, and serve to drive the individual vertical drive shafts 110 from the main drive shaft 50. Each of these gear units, as embodied, comprises a hollow casing 60, more or less rectangular in cross section, supported on the outside of bed frame 40 and held in close contact therewith. At one end of housing 60, there is provided a circular aperture over which is fitted a flange 61 secured to the end wall 62 by bolts 63, and in turn provided with a cylindrical aperture into which is fitted a ball bearing 64 mounted on shaft 50 by means of a tapered sleeve 65 and held on the tapered sleeve by means of collar 66. A cap 67 fits relatively tightly over shaft 50, closing the outer end of the cylindrical aperture in the sleeve 61 and also serving to retain ball bearing 64 in position, being fastened to the flange 61 by screws 68. Also, in the circular aperture in end wall 62 is mounted a roller bearing 69 which rotatably supports a long sleeve 70 extending for practically the entire length of the housing 60, and projecting from one end thereof and terminating in a flange 71. The other end wall 72 of the housing 60 is preferably provided with a larger circular opening into which is tightly fitted a plate 73 in which is mounted a roller bearing 74 for rotatably supporting sleeve 70, plate 73 being secured to the end wall 72 by screws 75. The cylindrical aperture covered by plate 73 is preferably sufficiently large to permit removal of shaft 50, bearings 74, 69 and the driving gear by axial movement.

Immediately adjacent to flange 71, there is provided a driving flange 77 which has its face against the outer face of flange 71. Flanges 71 and 77 are preferably provided with bushings 78 which may be placed in registry with each other and are apertured to receive a shear pin 79 which forms the driving connection between the flanges. Shear pin 79 is preferably held in position by means of plate 80 secured to flange 77 by screws 81, and pin 79 is provided with an enlarged head by which it may be removed when desired. Shear pin 79 is preferably grooved to reduce its diameter sufficiently so that its resistance to shearing is only slightly in excess of the normal driving load carried by it.

Immediately above sleeve 70 and secured to the upper portion of the housing 60 for gear unit 55 is provided a gear unit adapted to be driven from unit 55, and serving to drive the inking mechanism later to be described. This gear unit 83 comprises a housing 84 secured to

the upper surface of housing 60 by screws 85, the lower surface of housing 84 and the upper surface of housing 60 being machined to fit each other. Within housing 84 is mounted a worm 86 preferably formed integral with its shaft 87 which extends above and below it. The lower shaft end 87 is journalled in the housing 84 by means of ball bearing 88 seated in a suitable aperture in the bottom wall of housing 84, while the upper end of shaft 87 is similarly journalled by means of ball bearing 89 seated in a sleeve 90 which is fitted into an aperture in the upper wall of housing 84. Ball bearing 89 is pressed against shoulder 91 by means of a flange 92, which together with sleeve 90 is secured to the top wall of housing 84 by screws 93.

For driving shaft 87 and its worm 86 from sleeve 70, a bevel gear 95 is keyed to sleeve 70 and is driven and rotatably supported thereby, 20 meshing with a bevel gear 96 secured to the lower end of shaft 87 and held in place by the capping plate 97.

Worm 86 meshes with a worm gear 100 mounted to one side of worm 86 and having its shaft 101 extending at right angles to shaft 87. Shaft 101 is rotatably journalled in the side frames of housing 84 by means of roller bearings 102, one at either side of gear 100. For facilitating access to worm 86 and worm gear 100, and their associated parts within the housing 84, the top wall of housing 84 is apertured as at 103 and is provided with a removable cover 104.

Means are provided for driving the couples of the unit from the main drive shaft 50 through 35 gears 95, 96 and shaft 87, and for this purpose a vertical shaft 110 is provided above and in axial alignment with shaft 87, being coupled thereto by means of coupling flanges 111 fitted to the adjacent ends of shafts 87 and 110, and keyed to their 40 respective shafts. Flanges 111 are coupled together by means of bolts 112, and the flanges are retained on their respective shafts by means of coupling plates 113 and screws 114 threaded through the plates 113 and into the shaft ends. 45 Shaft 110 extends upwardly and is rotatably journalled in a gear unit housing 115 at one side of the printing couples, by means of a ball bearing 116 seated in the housing. Shaft 110 carries a bevel gear 117 meshing with a bevel gear 118 which is 50 rotatably journalled on a stud 120 projecting from the side frame 8, by means of ball bearings 121 and 122. The outer end of stud 120 is supported in an inner wall 123 of housing 115, and held rigid therein by nut 124 threaded on the 55 threaded end of the shaft. Nut 124 also serves to hold the bearings in proper spaced relation, pressing bearing 122 against sleeve 125, and thereby pressing bearing 121 against a ring 126 which abuts against the wall 123.

60 The hub portion of gear 118 is provided with an integral gear 130 adapted to mesh with and driving cylinder gears 30 and 31, driving them in the same direction.

65 An ink fountain is preferably provided for each of the printing couples, and is supported directly on the bed frames 40. This fountain comprises a relatively long, shallow and narrow trough 129 extending from one side frame 8 of the press to 70 the other side frame. At either end, the trough 129 is formed with a downwardly projecting portion 131 adapted to be bolted to the inner side of bed frame 40 by bolts 132, and a narrow vertical web 133 is provided extending between the portions 131, serving to support the bottom of the 75

fountain. The bottom of the fountain preferably slopes very slightly towards the center and a drain plug 134 is provided which may be removed for thorough cleaning of the fountain.

At its ends, the trough is also fastened to the 5 side frames 8 by means of laterally extending brackets 135 formed integrally with the trough 129 and screws 136 passing through the brackets 135 and threaded into the frame.

Within the trough, and dipping into the ink 10 retained therein, is a fountain roller 140 comprising a hollow roller of substantially the same length as the cylinders 5 and 6, and provided with shafts 141 and 142 secured to opposite ends of the roller by flanges 143 and 144 formed integrally 15 with their shafts, these flanges being secured to the roller ends by screws 145. Roller 140 is rotatably mounted by means of its shafts 141 and 142 in roller bearings 146 which are seated in bearing sleeves 147 and 148 secured in the lower 20 portions of the side frames 8. Bearings 146 on shaft 142 are held spaced apart by means of a spacing sleeve 149, and are held within the sleeve 148 by means of the retaining rings 150 and 151, these rings being secured to opposite ends of the sleeve 148 by screws 152. At the other end of the roller, the bearings 146 are mounted on shaft 141 and are spaced apart by means of a spacer ring 154, while the bearings are held together by shoulder 155 on shaft 141 with the inner portion of the hub of gear 156 keyed to shaft 141 and pressed inwardly by means of plate 157 and screw 158. Sleeve 147 is held in proper position in the frame 8 by means of screw 159 passing through the outer flange of sleeve 147 35 and threaded into the frame.

Means are provided for rotating the fountain roll 140 at a relatively slow speed, and for this purpose gear 160 keyed to the end of shaft 142 and secured thereon by cap 162, meshes with a gear 161 mounted on the end of shaft 101. The necessary slow speed of fountain roller 140 is obtained through the worm gearing 86, 100 and bevel gears 160 and 161. Gears 160 and 161 are housed within a housing 165 which also serves 40 to support the ball bearings 166 at either side of gear 161, the outer bearing being secured in place against a shoulder near the end of shaft 101 by means of screw 167 and cap 168, which are accessible by removal of plate 169 secured to the end 50 wall of housing 165 by screws 170.

Means are provided for removing surplus ink 5 from the fountain roller 140 and for regulating the quantity of ink to be fed from it to the printing couple, and for this purpose a scraper blade 175, of conventional construction, is mounted above the fountain roller, and variably pressed into contact with the surface of the fountain roller by means of the usual columnar adjusting means 176.

Means are provided for transferring ink from 6 the fountain roller to a series of ink forwarding and distributing rollers and drums which spread the ink into a uniform film and then apply it to the plates on the plate cylinder of the couple. As embodied, these transferring means comprise a 6 freely rotatable doctor roll mounted in arms which are adapted to be oscillated, first pressing the doctor roll against the fountain roller and then pressing it into contact with an ink drum mounted above it.

7 Doctor roll 180 is provided at its ends with reduced end portions 181 which are journalled in suitable bearings 182 carried at the outer ends of arms 183 which are clamped to shaft 184. Shaft 184 is mounted in suitable bearings in the side 7

frames 8, and at one end is provided with an arm 185 fixed to said shaft and projecting upwardly therefrom. Means are provided for oscillating shaft 184, and for this purpose a cam 186 formed integrally with a gear 187 is rotatably mounted by means of shaft 188 carried in ball bearings 189 seated in the frame 8, and bearings 190 seated in a suitable recess in the outer wall of housing 191 attached to the outside of frame 8. Gear 187 meshes with gear 156, keyed to the end of shaft 141 and is driven by rotation of fountain roller 140. Cooperating with cam 186 is a cam roller 192 freely rotatable on bolt 193 screwed into the end of yoke 194. Yoke 194 is provided with parallel guideways 195 which cooperate with a guide 196 freely rotatable on shaft 188, serving to hold yoke 194 against vertical movement. At its other end, yoke 194 is connected to a lever 198 freely oscillatable on shaft 184, the connection being effected through pivot pin 199. Movement of lever 198 is transmitted to arm 185 and thence to the doctor roller 180 by means of the opposed screws 200 threaded in lugs 201 which are formed integrally with a bracket 202 secured to the upper end of lever 198, the inner ends of these screws being adapted to be tightened against a bolt 502 fixed in the upper end of arm 185 to vary the angular position of the doctor roll 180 and thereby accommodate different sizes of rollers. After suitable adjustment, screws 200 and bolts 502 are tightened to securely hold arms 185 in proper position. Means are provided for pressing cam roller 192 against the surface of cam 186, and for resiliently pressing roller 180 into contact with fountain roller 140. For this purpose, a rod 205 is slidable in a cylindrical bore 206 formed in guide 196, and at its other end rod 205 is pivotally connected with yoke 194 by means of a screw 207 passing through an eyelet 208 at the end of rod 205. A helically coiled spring 209 encircles rod 205 and is compressed between eye 208 and guide 196, and slides back and forth on said rod as yoke 194 is reciprocated by cam 186.

An inking drum 210 is rotatably mounted by means of its shafts 211 which are rotatably journaled in the side frames 8, the inner ends of these shafts being provided with flanges 212 which are bolted to the drum body 210 by screws 213. Immediately above drum 210 is a similar drum 215, of slightly larger diameter, similarly mounted by means of its shafts 216, rotatably journaled in the side frames 8 and secured to the drum body by flanges 217 and screws 218.

Means are provided for rotating drums 210 and 215 by rotation of the cylinders of the printing couple, and for this purpose a gear 219 is formed integrally with the gear body of gear 34 or 36, at one end of the plate cylinder 6 of each couple. Gear 219 meshes with an intermediate gear 220 which in turn meshes with a gear 221 rigidly secured to the end of one shaft 216 by key 222 and cap 223. Gear 221 drives a pinion 224 rotatably mounted by ball bearings 225 on stud 226 projecting laterally from the side frame 8. Drum 210 is rotatably driven through its shaft 211 by means of gear 230 held rigid on the end of one shaft 211 by key 231 and cap 232, and meshes with idler 224. Preferably, cylinder 6, drums 215 and 210, rollers 180 and 140 have their axis in substantially vertical alinement.

Means are also provided for vibrating inking drums 210 and 215 as they rotate to facilitate uniform distribution of the ink on said drums, and for this purpose the shafts 211 and 216 are slidable in their respective bearings 235 and 236 in side frames 8, and gear 220 and idler 224 have sufficiently wide teeth to rotatably drive drums 210 and 215 as these drums are vibrated. At their ends opposite the gears 221 and 230, the shaft ends of drums 210 and 215 are of reduced diameter and are each provided with a bushing 238 fitted to the reduced shaft end and provided with an annular flange 239 of larger diameter formed integrally with the bushing 238. An outer circular plate 240 is provided and is held tightly against the bushing 238 by means of a screw 241 passing through the center of the plate and threaded into the shaft end. Positioned between plate 240 and flange 239 is a collar 242, and these collars for shafts 211 and 216 are pivotally connected to the opposite ends of bell crank 243 by means of pivot pins 244, projecting radially inwardly into suitable sockets in collars 242, and secured in the outer forked ends of bell crank 243. Bell crank 243 is pivotally mounted intermediate shafts 211 and 216 by means of a pivot pin 245 which is supported in bracket 246 secured to the outside of side frame 8. Bell crank 243 is formed with a laterally projecting arm 247 which is pivotally connected with link 248 by means of pivot pin 249, passing through an aperture in the upper end of link 248 and through similar apertures in the outer ends of forked arm 247.

Link 248 at its lower end is enlarged to form an eccentric strap 251 cooperating with eccentric 252 keyed to shaft 101 and driven thereby so that as the inking mechanism is driven, link 248 is reciprocated, causing vibration of inking drums 210 and 215.

Means are provided for transferring ink from drum 210 to drum 215 and from drum 215 to the plates on plate cylinder 6, as well as for distributing the ink on drums 210 and 215. For this purpose, transfer rollers 260 and form inking rollers 261 and 262 are rotatably mounted, each transfer roller contacting with drums 210 and 215, while the form inking rollers 261 and 262 contact with drum 215 and the plates on plate cylinder 6.

Means are provided for continuously circulating a relatively large quantity of oil or other lubricant, and for continuously supplying oil to all of the principal bearings and to all of the gear meshes while the press is in operation.

As embodied, the bottom of the oil tight housing 60 encloses an oil pump 311 which is submerged in the oil in said housing. Pump 311 is driven from main drive shaft 50 by means of pinion 314 fixed on shaft 50 and meshing with the pump gear 315. Pump 311 delivers oil under pressure to pipe 316 which is connected to pipes 317 by a T, and each pipe 317 is connected to a vertical pipe 318 extending upwardly on the left hand side of the press at one end of each plate cylinder and its cooperating inking drums. An oil supply pipe 318 extends vertically upward, and from it oil is supplied to bearings 6 for impression cylinder 5 by pipe 320, to housing 115 through pipe 321, to gear 130 through pipe 322 and thereby to gears 30 and 31, and also to gears 117 and 118 through pipe 333.

Oil is supplied to the bearings 9 on the right-hand side of cylinder 6 by means of a separate pump on the right side of the press which will be later described.

A gear housing is provided, which together with the side frame 8 on the left-hand side of the press, completely encloses gears 30, 31, and 130 and, as embodied, comprises the sections 340, 341, 342, 343, and 115, which are tightly fitted together in oil tight relation and secured to-

gether by bolts 344, and to the frame 8 by screws 345. These sections, taken together, are somewhat larger than the outside of gears 30, 31 and 130, and serve to retain and collect the oil supplied to the gears as it flows from these gears.

The oil supplied through oil pipe 321 is fed directly to oil hole 350 in stub shaft 120 through pipe 350', and flows through a downwardly inclined passageway 351 to communicate with oil groove 352 on shaft 120, also flowing through passageway 353 in spacer 125 and from there spreading outwardly to lubricate the ball bearings 121 and 122. The oil flowing through bearings 121 and 122, as well as the surplus oil from pipe 321 collects in the bottom portion 354 of casing 115, and gears 130 and 118 are lubricated as they dip down into this mass of oil in the concave bottom portion 354. A portion of the oil supplied to gear 117 through pipe 333 serves to lubricate ball bearing 116, and the excess flows through the bearing downwardly into the annular groove 355 which at one side communicates with the bottom portion 354. A flinger 356 extends from the bearing 116 downwardly and is provided with a conical lower portion of larger outside diameter than the inner wall of groove 355 and serves to prevent leakage of oil through the space between shaft 110 and housing 115. The surplus oil accumulating in the bottom portion 354 flows over the wall 357 and into the lower portion of housing 343.

Any excess oil supplied to the left hand bearings 9 and 16 is also collected in the housings 340, 341, 342, and 343.

For lubricating the vibrator yoke and bearings for the ink drums, the lower portion of housing 360 or 343 is connected with a drain pipe 368, extending downwardly and tapped into the upper wall of the vibrator housing 371. At 372, the wall is enlarged and formed with a tubular passage 370 which is provided with an aperture 373 directly above shaft 216, and is supplied with oil under pressure from pipe 370', so that oil flowing through the aperture 373 is collected and caught in cup 374 formed at the top of collar 242. Cup 374 communicates with the oil ducts 375 leading to oil grooves on pins 244, and also communicates with duct 376 which lubricates sleeve 242 on bushing 238.

For supplying the upper ink drum bearing 236 with oil, channel 360 is connected to passage 370 and communicates with the pocket 361 formed in the side frame 8. The outer and upper portion of the bearing bushing 236 extends upwardly across the outer face of the pocket 361 to retain a considerable amount of oil within the pocket, and the lower portion of the pocket communicates with an oil duct 362 leading to an oil hole and groove 363 in the bushing. At its inner end, bushing 236 is provided with an oil packing ring 365 retained in place by flange 366 screwed to the frame, and drained by passageway 366'. Lower bearing 235 is similarly supplied with oil from ledge 381 through pipe 360'.

A second oil hole 380 is also provided in the wall 372, and the oil flowing through hole 380 is caught on a narrow U-shaped ledge 381 formed integrally with and extending inwardly of housing 371, which also catches the oil from pipe 368. Ledge 381 is provided with holes 384 through which oil flows and is caught in pockets 385 formed on the upper surface of arms 247 of bell crank 243, which pockets supply oil to oil grooves 386 on pin 249. At its sides, ledge 381 is provided with oil holes 387 through which oil flows and

is caught by pockets 388, formed in bracket 246 and supplying oil to oil grooves 390 on pin 245. The surplus oil supplied to pocket 385 flows over the inner edge thereof and is supplied to a pocket 391 communicating with the oil tube 392 through which oil flows and is supplied to the cup 374 on the lower collar 242. The construction of the lower collar 242 is the same as that of the upper collar 242, and will not be described in detail.

The vibrator housing 371 is supported on and closely fitted to housing 395 enclosing the fountain roller driving gears, and housing 395 is formed with an upper wall 396 on which the surplus oil from pockets 361 and holes 373 and 380 accumulate. This wall 396 is apertured to provide an opening through which extends the link 248, and the surplus oil flows over the edge of this aperture into cup 398 formed on the lower portion link 248 and above the eccentric strap 251, communicating with the eccentric by means of oil duct 399. The oil flowing over plate 396 collects in the bottom of the housing 395 and gear 160 dips into this mass of oil as it rotates, and a sufficient quantity of oil is always maintained in the housing to bring the oil level above the bottom of bearings 146, while leakage of the oil through the bearings is prevented by packing ring 400.

Means are provided for withdrawing surplus oil from the housing 395 and returning it to the reservoir in the bottom of housing 60, and for this purpose an overflow pipe 401 is tapped into the outer wall of housing 395, and is connected to a horizontal pipe 402 which returns the oil through pipe 403, and hand hole cover 404, covering an aperture 405 formed in the outer side wall of housing 60.

The bearings and gear meshes on the right-hand side of the press are also supplied with oil by pump 311', which supplies oil under pressure to pipe 317' which in turn is connected with vertical pipes 410, one for each couple, extending upwardly on the outside of the side frame 8 and adjacent to the right end of the ink drums and plate cylinder. Pump 311' is mounted in a sump 446' and is driven from gear 156 through idler 451. As embodied, pipe 410 delivers oil under pressure to pipes 411 and 412 supplying oil to the plate and impression cylinder bearings 9 and 16. Pipe 410 is also connected with pipe 414 terminating at a point slightly below the mesh of gears 33 and 34 or 35 and 36, and oil is supplied to the mesh between gears 219 and 220 or 219' and 220 by a pipe 415. Pipe 416 is positioned immediately below gear 220 and delivers oil to the mesh point between gears 220 and 221, while pipe 417 supplies oil to the mesh between gears 221 and 224 and pipe 418 supplies oil to the mesh between gears 224 and 230.

Oil is supplied to the bearings for idler gear 224 through pipe 420 which passes through the side wall of casing 421 enclosing the inking drive gears and is connected to the end of stub shaft 226 to communicate with passageway 422, which, in turn, communicates and supplies oil to oil groove 423 and bearings 224 and 225. A similar oil pipe 425 is provided for supplying oil to the bearings for gear 220 which may be similarly mounted.

The upper oil pocket 361 on the right hand side is supplied with oil from the oil pipe 425 which feeds oil to oil pipe 410' for shafts 211 and 216. Inasmuch as these oil pockets are similar to those at the left-hand end of the shafts, they will not be again described in detail. The lower

oil pocket 361 on the right side is supplied with oil from pipe 420' which is in communication with oil passageway 422.

The surplus oil supplied to the gears through pipes 414 and 415 is retained adjacent to the gears by the gear housing 427 secured to the outside of the press frame 8 and enclosing the gears, and at its lower end is open to communicate with the open upper end of the housing 421. Housing 421 is also supported on press frame 8 and is bolted to the upper flat surface of a housing 428 enclosing gear 230 and the fountain roller and ductor gears. In its upper portion housing 428 is provided with a concave wall 430 extending around the lower portion of gear 230, and forming with the side frame of the press and web 431 an oil pocket which retains a considerable amount of oil and provides an oil bath for gear 230. Near its bottom, wall 430 is apertured to receive a pipe 432 which takes oil from the oil bath and leads it to an oil pocket 434 formed at one corner of the casing 191 and provided with an oil hole 435 through which oil drains to the bearings on shaft 184.

Means are also provided for continuously supplying oil to the ink vibrating mechanism and for this purpose the excess oil supplied through pipes 414, 415, 416, 417, 418, 420, 425, and 426 collects in the pocket formed by wall 430, and the excess oil which is not drained off through pipe 432 flows over the upper edge of web 431 and through passageway 436 and on to the horizontal web 437 extending from the outer wall of housing 428 to a point closely adjacent to the side frame 8. Web 437 is apertured at 438, and the oil accumulating on the surface of the web drips downwardly into a pocket 439 extending longitudinally of and formed as an integral part of the yoke or link 194. Longitudinal pocket 438 is divided into two end-to-end sections by means of a web 439' extending between the side walls 440 of the pocket, and the excess oil flowing into the left-hand portion of pocket 439 flows over the web 439' and into the right-hand pocket 439, these pockets supplying oil holes 443 and 441 respectively. Housing 428 is oil tight and encloses all of the vibrator drive mechanism, and its lower wall is provided with a drain plug 442 which may be removed for changing the oil.

As the surplus oil accumulates in the bottom of the housing 428, the excess is drained off through pipe 445 which extends to one end of the unit and is inclined downwardly towards sump 446' within which is located the right hand press driven pump. This oil which collects in the bottom of housing 428 is below the level of drain pipe 445 and provides an oil bath for the vibrator driving mechanism, as well as the fountain roller bearings 146, the oil being retained within the bearings by means of oil-tight packing ring 446. In the rear housing 428, bearings 146 are lubricated by oil flowing through oil groove 447.

Suitable oil pressure gauges 448 may be provided for indicating proper functioning of the oiling system.

Means are provided for lubricating the ductor roller bearings at the ends of shaft 181, and for this purpose grease fittings 450 are provided threaded into the bearings 182 and through which grease may be supplied for this bearing.

By reason of the present invention, the units may be easily disassembled for shipment and may

be easily erected in the field with the certainty that the parts will be properly fitted. After the press has been completely assembled, as in the factory, it may be prepared for shipment, as follows: The main driving shaft 50 with its bearings and the main driving gears within housing 60 are removed as a unit. The upper portion of housing 342 is removed, the outer part 115 of the housing is removed and drive shaft 110 may then be removed.

Thereafter, the cylinders 5 and 6, with their gears, bearings and impression adjustment may be lifted after removal of caps 26. The ink drum shafts 211 and 216 are unbolted from the drum bodies 210 and 215, and the frames are moved apart to permit removal of the fountain roller body and the drum bodies 210 and 215. In this manner, the principal bearings and gear meshes are not disturbed, and there can be no danger of improper setting of the gears or bearings when the press is reassembled for use. When disassembled, the parts are very compact, not unduly large or heavy, and none of the parts require unusual care in shipment, thereby avoiding the expense which has heretofore been necessary in completely disassembling and reassembling the parts of the press.

Means are also provided for optionally and alternatively running either printing couple in the reverse direction whereby each unit may print one side of a web in two colors, and by running the web through two printing couples, the web may be printed three colors on one side and one color on the other, or may be perfected in two colors. As embodied, a stub shaft 461 is provided, projecting outwardly from the right hand side frame 8, and positioned medianly between gears 33 and 35. Shaft 461 is adapted to rotatably support an idler 460, meshing with gears 33 and 35, and when used, causes all of the cylinders to be driven from gear 34 or gear 36.

After gear 460 has been put in place, gear 31 may be moved from its shaft, so that the couples are driven from gear 130, through gears 30 and 36, or alternatively, the toothed ring of gear 30 may be moved driving both of the couples from gear 130 through gears 31 and 34.

When reversing either of the couples, it is not necessary to make any changes in the inking apparatus as the drums, rollers and fountain roll always rotate in the proper direction with respect to their respective plate cylinders.

The invention in its broader aspects is not limited to the specific mechanisms shown and described but departures may be made therefrom within the scope of the accompanying claims without departing from the principles of the invention and without sacrificing its chief advantages.

What I claim is:

1. In a rotary newspaper printing unit the combination of a pair of printing couples, a driving gear meshing with a removable gear on one cylinder of each couple and a gear on each cylinder at the other end of said cylinders, the gears of each couple meshing with each other, a removable idler meshing with a gear of each couple on said other side, whereby either of said removable gears may be moved out of mesh with said driving gear to drive the couples in either direction through said idler, inking drums for each couple driven by the plate cylinder of its couple, and a fountain roller for each couple, and means for driving the inking mechanism always in the same direction.

2. In a rotary newspaper printing unit, the

combination of a pair of printing couples, a gear on one plate cylinder shaft, a gear on the impression cylinder shaft of the other couple, a driving gear meshing with said gears, a gear on each plate cylinder shaft at the other end of the cylinders meshing with a gear on the shaft of the cooperating impression cylinder, an idler meshing with the impression cylinder gears, said idler being removable and one of said first two gears 10 being removable whereby the couples may perfect a web, or the plate cylinders may be driven in either direction for multi-color.

3. In a printing press, the combination of a pair of printing couples, an inking train for each couple, a main drive shaft, a unit drive shaft for driving said printing couples and inking mechanism, shafts for driving said inking trains from said unit drive shaft independently of the drive for the couples, and gearing removable as a unit between said main shaft and unit drive shaft whereby the drive for the inking trains does not carry the driving load of the printing couples.

4. In a printing press, the combination of a side frame in which are journalled the cylinders 25 of a rotary printing couple and ink drums therefor, gearing for driving one cylinder and the inking drums from the other cylinder and an oil tight housing enclosing said gearing, and means for supplying a continuous flow of oil to the upper 30 part of said housing to lubricate the upper gears and bearings and to cause a surplus to flow down freely within the housing to lubricate the lower gears and bearings.

5. In a printing press, the combination of a 35 rotary printing couple, inking mechanism therefor, a fountain roller, a unit drive shaft driving the fountain roller and couple, means for driving the inking mechanism from the couple, an oil-tight housing enclosing the driving mechanism for the couple, inking mechanism and roller, means for continuously supplying oil to the driving mechanism and journals at a plurality of points within said housing and for causing surplus oil to flow freely down from one journal to another, 40 said housing serving to collect the excess oil and means for withdrawing oil from the bottom of said housing.

6. A rotary newspaper printing unit including in combination a pair of side frames, printing 50 cylinders, inking drums and fountain rollers journalled in said frames, drum vibrating means, gearing for driving said cylinders, drums, fountain rollers, and vibrating means, said drums and rollers being detachable from their shaft ends, whereby the roller and drum bodies may be removed and the side frames may be shipped with the shaft ends and vibrating means in place.

7. A rotary newspaper printing unit including 60 in combination a pair of side frames, printing cylinders, inking drums and fountain rollers journalled in said frames, drum vibrating means, a unit drive shaft from which the drums, cylinders, fountain rollers and vibrating means are 65 driven, said drums and rollers being detachable from their shaft ends, an ink trough and tie bar for bracing the side frames, whereby the cylinders, drum and roller bodies, ink trough and tie bar may be removed for shipment and the side frames may be shipped without disassembly of the vibrating means, fountain and drum bearings and driving means.

8. In a printing press, the combination of a 70 printing couple, a main drive shaft, a unit drive shaft geared to the couple, a sleeve rotatable on

said main shaft, a gear fast on said sleeve to drive said unit drive shaft, an oil housing surrounding said gear and a portion of said sleeve, a collar adjacent to one end of said sleeve and fast to said main shaft and a shear pin coupling 5 said collar and sleeve together.

9. In a printing press, the combination of a plurality of printing couples arranged in line, each of which has its own drive shaft, a main drive shaft extending between and adapted to 10 drive all of said couples, and means for driving each unit from said main shaft including gears loose on said main shaft, for driving said unit drive shafts, a collar adjacent to each of said gears and shear pins connecting each collar 15 with its respective gear.

10. In a printing press, the combination of a plurality of printing couples arranged in line, each of which has its own drive shaft, a main drive shaft extending between and adapted to 20 drive all of said couples, and means for driving each unit from said main shaft including gears loose on said main shaft, for driving said unit drive shafts, a collar abutting each of said gears, and shear pins connecting each collar to its respective gear, said collars and gears being provided with a single pin hole whereby registry of the several couples is assured.

11. In a printing press, the combination of a 25 printing couple, a main drive shaft, a unit drive shaft geared to the couple, a sleeve rotatable on said main shaft, a gear fast on said sleeve to drive said unit drive shaft, a collar adjacent to one end of said sleeve and fast to said main shaft and a shear pin coupling said collar and 30 sleeve together.

12. In a rotary printing press, a printing unit comprising at least one couple of printing cylinders journalled within the frame of the unit, an inking train for said couple consisting of a plurality of rollers journalled in said frame, gearing for driving said cylinders and the rollers of the inking train, at least some of said bearings and gears being arranged on different levels to the others, means for supplying an excess of 45 lubricant to the gears of the printing couple at the uppermost part of the unit and means for directing the excess lubricant from said uppermost gears directly to the lower bearings and gears of the inking train of the same unit.

13. In a rotary printing press, a printing unit as claimed in claim 12 in which the lubricant is supplied to the gears and bearings in a continuous flow from a source of supply individual to the unit and is returned to said source of supply 55 after completion of its circuit.

14. In a rotary printing press, a printing unit as claimed in claim 12, in which the means for directing the excess lubricant to the lower bearings comprise a plurality of oil cups communicating with said bearings, the lubricant supplied to the uppermost gears being conducted downwards successively from cup to cup by means for conducting the overflow from the cups.

15. In a rotary printing press, a printing unit 65 as claimed in claim 12, in which the gearing for driving the printing couple is enclosed in an oil-tight housing, means being provided for supplying lubricant to said housing at one or more points and for retaining a bath of lubricant within said housing in which said gearing is immersed.

16. A rotary newspaper printing unit including in combination a pair of side frames, printing cylinders, inking drums and fountain rollers 70

5 journalled in said frames, drum vibrating means, gearing for driving said cylinders, drums, fountain rollers, and vibrating means, some of said drums and rollers being detachable from their shaft ends, whereby the roller and drum bodies may be removed and the side frames may be shipped with certain of the shaft ends, gearing and the vibrating means in place.

17. A rotary newspaper printing unit including in combination a pair of side frames, printing cylinders, inking drums and fountain rollers journalled in said frames, drum vibrating means, gearing for driving said cylinders, drums, fountain rollers, and vibrating means, some of said drums and rollers being detachable from their shaft ends, whereby the roller and drum bodies may be removed and the side frames may be shipped with certain of the shaft ends and the vibrating means in place.

20 18. A rotary newspaper printing unit including in combination a pair of side frames, printing cylinders, inking drums and fountain rollers journalled in said frames, drum vibrating means, gearing for driving said cylinders, drums, fountain rollers, and vibrating means, oil housings enclosing said gearing and the shaft ends of the cylinders, drums and rollers, said drums and rollers being detachable from their shaft ends, whereby the roller and drum bodies may be removed and the side frames may be shipped with the shaft ends, oil housings and vibrating means in place.

19. A rotary newspaper printing unit including in combination a pair of side frames, printing cylinders, inking drums and fountain rollers journalled in said frames, drum vibrating means, gearing for driving said cylinders, drums, fountain rollers, and vibrating means, oil housings enclosing said gearing and the shaft ends of the cylinders, drums and rollers, some of said drums and rollers being detachable from their shaft ends, whereby the roller and drum bodies may be removed and the side frames may be shipped with certain of the shaft ends, gearing, oil housings and vibrating means in place.

20 21. A rotary newspaper printing unit including in combination a pair of side frames, printing cylinders, inking drums and fountain rollers journalled in said frames, drum vibrating means, gearing for driving said cylinders, drums, fountain rollers, and vibrating means, oil housings enclosing said gearing and the shaft ends of the cylinders, drums and rollers, some of said drums and rollers being detachable from their shaft ends, whereby the roller and drum bodies may be removed and the side frames may be shipped with certain of the shaft ends, oil housings and the vibrating means in place.

21. A rotary newspaper printing unit including in combination a pair of side frames, printing cylinders, inking drums and fountain rollers journalled in said frames, drum vibrating means, a unit drive shaft from which the drums, cylinders, fountain rollers and vibrating means are driven, some of said drums and rollers being detachable from their shaft ends, an ink trough and tie bar for bracing the side frames, whereby the cylinders, drum and rollers bodies, ink trough and tie bar may be removed for shipment and the side frames may be shipped without disassembly of certain of the vibrating means, fountain and drum bearings and the driving means.

22. A rotary newspaper printing unit including in combination a pair of side frames, printing cylinders, inking drums and fountain rollers jour-

5 nalled in said frames, drum vibrating means, oil housings enclosing the gearing and shaft ends of the cylinders, drums and rollers, a unit drive shaft from which the drums, cylinders, fountain rollers and vibrating means are driven, some of said drums and rollers being detachable from their shaft ends, an ink trough and tie bar for bracing the side frames, whereby the cylinders, drum and roller bodies, ink trough and tie bar may be removed for shipment and the side frames 10 may be shipped without disassembly of certain of the vibrating means, fountain and drum bearings, oil housings and the driving means.

23. In a rotary newspaper printing unit the combination of a pair of printing couples, a driving gear normally driving the impression cylinder of one couple and the plate cylinder of the other couple and located at one side of the press, means for silencing the drive to either one of the couples, gears at the other side of the press 15 interconnecting the cylinders for driving the other cylinder of each couple from the driven cylinder and optionally operable means for reversely driving either couple from the other couple.

24. In a rotary newspaper printing unit the combination of a pair of printing couples, a driving gear normally driving the impression cylinder of one couple and the plate cylinder of the other couple, means for silencing the drive to either one of the couples, gears interconnecting 20 the cylinders for driving the other cylinder of each couple from the driven cylinder and optionally operable means for reversely driving either couple from the other couple.

25. In a rotary printing unit a pair of spaced 35 apart press side frames, printing couples and inking mechanisms therefor mounted between the press frames, ink fountains at the bottom of said frames and spacing said side frames and a cross brace between the side frames and between the 40 couples, said brace being relatively wide and having narrow slots extending across the width of the press through which a web may be led from one couple to the other.

26. In a rotary printing press unit, a pair of 45 printing couples, side frames in which said couples are mounted, inking mechanism for said couples including ink fountains bracing said side frames near their bottoms, and a slotted cross brace between the side frames and between the couples, 50 the slots permitting a web to be led from one couple to the other.

27. In a rotary printing press, the combination of a vertical drive shaft, a printing couple, gearing for driving the printing couple from the vertical shaft, a portion of said gearing being mounted on said shaft, a housing enclosing said gearing and at least a portion of the shaft, a bearing for the shaft carried by the housing, said housing having an aperture for the shaft, means for supplying oil to said gearing, and a finger for throwing excess oil draining from the bearing away from the vertical shaft and housing aperture to prevent leakage from the housing.

28. In a rotary printing press, the combination of a vertical drive shaft, a printing couple, gearing for driving the printing couple from the vertical shaft, a portion of said gearing being mounted on said shaft, a housing enclosing said gearing 65 and at least a portion of the shaft, a bearing for the shaft carried by the housing, said housing having an aperture for the shaft, an oil pipe forcing oil into the shaft supported gear, means for conducting a portion of the oil from the gear to 70 75

the bearing and an enlarged member between the bearing and aperture to prevent leakage of oil down the shaft through the aperture, said enlarged member serving to throw oil from the shaft 5 and retain it in the housing.

29. In a printing press, the combination of side frames in which are journalled the cylinders of a rotary printing couple and the ink drums therefor, a drive shaft, bearing for driving the couple 10 from the drive shaft, gearing for driving the inking drums, means for vibrating the inking drums, said gearing and vibrating means being enclosed within oil collecting housing means and means for supplying a flow of oil to the couple driving

gear, to the vibrating means and to the drum gearing.

30. In a printing press, the combination of side frames in which are journalled the cylinders of a rotary printing couple and the ink drums therefor, a drive shaft, gearing for driving the inking drums, means for vibrating the inking drums, said gearing and vibrating means being enclosed within oil collecting housing means, means for supplying a flow of oil to the couple driving gear, 5 to the vibrating means and to the drum gearing, and means for returning the oil collected by the housing means to the supplying means. 10
